(57) **CLAIM**

The ornamental design for a utility knife handle, as shown and described.

DESCRIPTION

FIG. 1 is a front perspective view of the utility knife handle of the present invention showing my new design;

FIG. 2 is a side elevational view thereof;

FIG. 3 is an opposite side elevational view thereof;

FIG. 4 is a back elevational view thereof;

FIG. 5 is a front elevational view thereof;

FIG. 6 is a top plan view thereof;

FIG. 7 is a bottom plan view thereof; and,

FIG. 8 is a rear perspective view of the utility knife handle of the present invention.

The broken lines illustrating a blade holder and a blade are directed to environment and form no part of the claim. All other broken lines in the drawings illustrate unclaimed features of the handle.
